UNITED STATES PATENT OFFICE.

ARTHUR E. PETERS, OF EASTON, PENNSYLVANIA, ASSIGNOR TO INGERSOLL-RAND COMPANY, OF JERSEY CITY, NEW JERSEY, A CORPORATION OF NEW JERSEY.

EMERGENCY-STOP FOR STEAM-ENGINES.

1,324,064.

Specification of Letters Patent.

Patented Dec. 9, 1919.

Application filed March 29, 1917. Serial No. 158,279.

To all whom it may concern:

Be it known that I, ARTHUR E. PETERS, a citizen of the United States, residing at Easton, in the county of Northampton and State 5 of Pennsylvania, have invented a certain new and useful Improvement in Emergency-Stops for Steam-Engines, of which the following is a specification.

This invention relates to an emergency 10 stop for steam engines, and more particularly to a device of this kind for use with steam engines of the puppet valve type.

The object of the present invention is to provide a simple and effective emergency 15 stop, particularly adapted for use with steam engine valves of the puppet type whereby the steam admission will be automatically cut off and the engine brought to rest when the engine speed attains a pre- 20 determined maximum due to the failure to operate of the main governing means by which such engines are ordinarily controlled, thus contributing to the safety and efficiency of the engine.

25 The above object is accomplished by the device, a practical embodiment of which is represented in the accompanying drawings, in which:

Figure 1 is a view of the steam cylinder, 30 inlet valve and emergency stop mechanism in end elevation, certain of the parts being illustrated in section,

Fig. 2, a top plan view of the steam cylinder, the governor lay shaft and the emergency stop lay shaft,

Fig. 3, a cross sectional elevation of a modified form of my invention,

Fig. 4, a sectional view of the tripping means used in connection with my emergency stop mechanism with the plunger in 40 extended position, and

Fig. 5, a similar view of the tripping means with the plunger in retracted position.

45 In the drawings is shown a steam cylinder 1 provided with inlet valves 2 and exhaust valves, not shown. Mounted parallel to the cylinder 1 on brackets or arms 3, 3, projecting therefrom, is a governor lay shaft 4, driven in any desired manner, as, for instance, by gearing or link belt from the engine shaft. On this lay shaft 4 are mounted inlet valve operating eccentrics 5, and exhaust valve operating eccentrics 6, the construction and operation of which form no

part of the present invention, these parts being fully described in my patent No. 1,299,-793 granted April 8, 1919. From the inlet valve operating eccentrics 5, rods 7 extend to the inlet valve bonnet 2, similar rods (not shown) also connecting the exhaust valve operating eccentrics 6 with the exhaust valve bonnets. The inlet valve operating rods 7, at one extremity are each secured to one end of a cam 8, the other end of which engages one arm of a bell crank lever 9 to raise the valve plunger 10 to admit operating fluid to the engine cylinder 1. These cams 8 rock on pins 11, mounted in the projecting lugs 12 of the valve bonnet. The pins 11 which rotate in bearings provided for them in the lugs 12 of the valve bonnets have in their central section an eccentric portion 12^a. It is about this section of the pins 11 that the cam 8 oscillates when the engine is running under normal conditions. It will be seen that a rotative movement of the pin 11 will, by virtue of the eccentric portion 12^a throw the cam away from bell crank 9. The cams 75 8 may, if desired, be constructed in the form shown in Fig. 3, thus eliminating the bell cranks 9. To one of the projecting ends of each valve pin 11 there is made fast one end of a short crank arm 13, the opposite ends of these crank arms 13 being pivoted to connecting rods 14 the opposite ends of which rods are, in turn, pivoted to crank arms 15 secured on lay shaft 16, mounted on the bearings or arms 3, parallel to the cylinder and eccentric shaft 4. To one end of this 80 intermediate shaft 16 there is collared a bell crank lever 17, one arm of this lever forming a cam 18 projecting in the direction of the eccentric shaft 4, the purpose of which will be hereinafter set forth. To the other arm 85 of this bell crank lever 17, a weight 19 is suspended in a manner so that it is normally 90 locked against falling.

Journaled on the eccentric or lay shaft 4, and arranged to rotate therewith, is a cylindrical collar 20 having a hollow projecting portion 21. In this projecting portion 21 is fitted a plunger 22 having a body portion, a central tapered portion and a projecting pin portion. The body portion of the plunger 22 is normally retained close to the lay shaft 4 in the following manner. The projecting portion 21 of the collar 20 is provided with a series of holes 23 into which fit balls 24, these balls extending slightly 100 105 110

beyond the wall of the projecting portion 21 and so located as to rest against the tapered plunger portion to normally retain the plunger in retracted position against 5 the eccentric or lay shaft 4. Disposed circumferentially of the projecting portion 21 of the collar 20 is a cylindrical weight 25 which rests with a tapered fit against the collar 20 when in closed position, and serves 10 to retain the balls 24 in their normal position and hence the plunger 22 in its normal position, as above described. The weight 25 is provided with an axial recessed portion 26 in its outer end which forms a seat for a 15 coiled spring 27, the other end of which bears upon a washer 28 resting against the flanged portion 29 of an adjusting nut 30 threaded in the interior of the projecting collar portion 21. This nut 30 has an axial 20 passage through which the pin portion of the plunger projects, the inner end of this passage being recessed to provide a seat for the tapered portion of the plunger when it assumes its open or operative position. The 25 collar portion 21 is secured to the lay shaft 16 by means of a set screw 31 and key 32.

The operation of the steam engine is ordinarily controlled by any form of governing mechanism, which forms no part of the 30 present invention, so that the engine will at no time attain a speed sufficient to cause the operation of the present emergency stop mechanism to occur while thus controlled. When, however, the governor breaks down, 35 or for any other reason loses control of the engine, the engine will speed up to a predetermined extra maximum, rendering the emergency stop mechanism operative in the following manner. The spring 27, before 40 mentioned, is calibrated to withstand the centrifugal force exerted upon it by the weight 25 during the normal rotation of the governor lay shaft 4, and up to the predetermined extra maximum speed referred to, 45 and is adjustable to various speeds by an increase or decrease in its tension, through manipulation of the adjusting nut 30. When this predetermined extra maximum speed is exceeded the tension of the spring is over- 50 come by the centrifugal force exerted by the weight 25, which thereupon compresses the spring and moves outwardly. When this action takes place the plunger 22 is released and flies out, the balls 24 moving into the 55 passage formed between the tapered opposing faces of the weight 25 and collar 20 and being retained therein. Upon flying out the plunger 22 will in its rotation engage the cam 18 on the bell crank lever 17, hereinbefore referred to, rotating this bell crank sufficiently to throw the point of suspension of the weight 19 off center, thus tripping the weight and causing it to fall. The falling 60 of the weight 19 will further rotate the bell 65 crank 17 to impart a rotative movement to

the intermediate lay shaft 16 and hence a downward movement to the connecting rods 14, through the crank arms 15, which will, in turn, through the agency of the cranks 13, cause the eccentric pins 11 to rotate in 70 the lugs 12 in a direction to force the cams 8 away from the bell cranks 9 and thus withdrawing them therefrom sufficiently so that the cams 8 do not come in contact with the bell cranks 9. The weight 19 in its lower position serves to maintain the valve operating parts out of operation, as any motion transmitted to the cams 8 by the operating rods 7 will cause them to merely rock idly without 75 engaging the valve operating bell cranks 9. 80 Thus, upon the failure of the inlet valves 2 to operate to supply motive fluid to the cylinder 1, the engine will speedily come to rest. The plunger 22 is then caused to resume its normal position by being manually 85 pressed inwardly against the lay shaft and the lifting of the weight 19 will bring the valve operating parts again into operative position for re-starting of the engine.

It is to be understood that various changes 90 might be resorted to in the construction, form, and arrangement of the various parts of this invention, and that while the present showing and description discloses only certain specific embodiments thereof, other 95 forms and modifications are included within the spirit and scope thereof, as expressed in the appended claims.

What I claim is:

1. In an emergency stop for steam engines, a lay shaft, an eccentrically mounted valve operating cam, means associated therewith for actuating said cam, a rod arranged to vary the position of said cam and centrifugal means on the lay shaft arranged to engage means to actuate the said rod to render the valve operating means inoperative when the engine speed attains a predetermined maximum.

2. In an emergency stop for steam engines, a lay shaft, valve operating means associated with the lay shaft, a plunger mounted on said lay shaft normally retained in inoperative position and means for releasing the said plunger when the engine speed attains a predetermined maximum to render the valve operating means inoperative.

3. In an emergency stop for steam engines, a lay shaft, an eccentrically mounted valve operating cam, means associated therewith for actuating said cam, intermediate means for varying the position of the eccentric mounting of said cam and a plunger on the lay shaft normally retained in retracted position and adapted to be released to engage means to actuate said intermediate means, rendering the valve operating cams inoperative, when the engine speed attains a predetermined maximum.

4. In an emergency stop for steam en- 130

gines, a lay shaft, an eccentrically mounted valve operating cam, mechanism associated with said lay shaft for actuating said cam, a rod secured to the eccentric mounting of 5 said cam, an intermediate shaft, a cam projecting therefrom, a plunger journaled on the lay shaft normally retained in inoperative position and centrifugal means for releasing said plunger to engage said projecting cam to vary the position of the eccentric center of said valve operating cam, rendering the same inoperative, when the engine 10 speed attains a predetermined maximum.

5. In an emergency stop for steam engines, a lay shaft, an eccentrically mounted valve operating cam, mechanism associated with the lay shaft for actuating said cam, an intermediate shaft mounted parallel to the cylinder and lay shaft, a rod connecting said 20 intermediate shaft and valve operating cam, a bell crank portion on one end of said intermediate shaft one arm of which forms a projecting cam and the other a support for tripping means, a plunger journaled on the lay shaft and centrifugal means for releasing said plunger to engage the projecting cam and rotate the intermediate shaft thereby actuating the tripping means and causing said rod to alter the position of the 25 valve operating cam to render the same inoperative when the engine speed attains a predetermined maximum.

6. In a tripping means for operating a safety stop mechanism for engines, a rotating arm carrying a spring pressed centrifugal member and a plunger, said plunger be-

ing released when the spring pressed centrifugal member moves outwardly.

7. In a tripping means for operating a safety stop mechanism for engines, a rotating arm, a centrifugal member movable on 40 said arm, a spring retaining said centrifugal member in retracted position and a plunger movable outwardly to engage a cam movement of said cam operating means to render 45 inoperative the admission valve mechanism when the speed of the engine exceeds a maximum.

8. In a tripping means for operating a safety stop mechanism for engines, a rotating arm, a centrifugal member movable on 50 said arm, a spring retaining said centrifugal member in retracted position, a plurality of balls normally holding a plunger in retracted position in said arm, said plunger being 55 released when the centrifugal member moves outwardly.

9. In a tripping means for operating a safety stop mechanism for engines, a rotating arm, a centrifugal member movable on said 60 arm, a spring retaining said centrifugal member in retracted position, a plurality of balls engaging said centrifugal member and normally holding a plunger in retracted position in said arm, said plunger adapted to 65 move outwardly to engage means to render inoperative the admission valve mechanism when the speed of the engine exceeds a maximum.

In testimony whereof I have hereunto set 70 my hand.

ARTHUR E. PETERS.
